UNITED STATES PATENT OFFICE.

MILTON S. CABELL, OF QUINCY, ILLINOIS, ASSIGNOR OF ONE-HALF TO
WILLIAM SCHAEFER, OF SAME PLACE.

LUBRICATOR FOR ENGINE-SLIDES.

SPECIFICATION forming part of Letters Patent No. 289,066, dated November 27, 1883.

Application filed August 20, 1883. (No model.)

To all whom it may concern:

Be it known that I, MILTON S. CABELL, of Quincy, in the county of Adams and State of Illinois, have invented certain Improvements 5 in Lubricators for Engine-Slides, of which the following is a specification.

The aim of my invention is to provide a simple and efficient means for lubricating the cross-head slides of steam-engines, pumps, and 10 similar machinery.

To this end the invention consists in combining with the slide an oil-reservoir connected to its side and communicating with an opening entering from one side and emerging 15 from the face of the slide, whereby the oil is delivered to the wearing-surface of the slide and caused to work thence over all the wearing-surfaces.

Referring to the accompanying drawings, 20 Figure 1 represents a vertical section of the cross-head and guides provided with my improvement. Fig. 2 is a top plan view of the same.

Referring to the drawings, A represents an 25 ordinary reciprocating cross-head; B B, the two parallel slides by which the ends of the cross-heads are sustained; C C, two oil-reservoirs, and D D two pipes connecting the reservoirs with the respective slides. It will be 30 observed that the pipes D extend downward from the reservoirs to the slides, and that they communicate with openings E, which enter the sides of the slides and emerge therefrom on one of the wearing-faces. Under this arrangement it will be perceived that the oil, 35 descending by gravity, will be delivered through the opening in the face of the slide in position to be acted upon by the cross-head, which serves to distribute the same over the entire

length of the slide and to cause it to work 40 downward over all the wearing-surfaces. The oil-reservoir may be of any ordinary or suitable construction. Each cup or reservoir is preferably connected with the pipe D by means of a screw-joint or other connection which 45 will admit of its being readily detached. Each of the feed-pipes is preferably provided with a cock or equivalent device by which the flow of oil may be regulated or stopped.

The essential feature of the invention consists in combining an oil-reservoir with a discharge-tube and a passage leading through the slide, substantially as described.

The details may be modified provided no departure is made from the mode of action 55 herein described.

The present invention is restricted to those matters and things which are hereinafter claimed, and as to all matters which may be described or shown, but which are not claimed, 60 the right is reserved to make the same the subject of a separate application.

Having thus described my invention, what I claim is—

1. In combination with the reciprocating cross-head, the horizontal stationary guides, each having an oil-passage extending downward through its upper surface and outward through its side, and the elevated oil reservoirs or cups connected with said passages.
2. The combination of the stationary guides provided with oil-passages, the reciprocating cross-head, and the elevated cups or reservoirs connected with the openings.

MILTON S. CABELL.
